RAILWAY TRUCK

Donald S. Barrows, Rochester, N. Y., assignor to
The Symington-Gould Corporation, Rochester,
N. Y., a corporation of Maryland

Application April 26, 1935, Serial No. 18,468

20 Claims. (Cl. 105—186)

This invention relates to railway vehicles and, more particularly, to trucks and the construction of the side frames, bolsters, and associated parts.

The principal object of my invention, generally considered, is to improve the construction of railway trucks, and, particularly, that of the side frames, bolsters, and/or associated parts, in order to facilitate assembly and detachment of the parts of such trucks, and provide for lateral motion of the bolster with respect to the associated side frames, while allowing a limited amount of angling of the bolster with respect to said frames.

Another object of my invention is the provision of a railway truck comprising side frames, an associated bolster, bolster-supporting springs, and shoes between each side of the bolster and the associated guide column, anti-friction means being disposed between the bottom of the bolster and the top of the supporting springs, so that said bolster is allowed to move laterally with respect to the associated frames, the arrangement including shoes between each side of the bolster and said guide columns, said shoes being formed to angle a limited amount with respect to said guide columns, while allowing lateral motion of the bolster with respect thereto.

A further object of my invention is the provision of a railway truck in which the bolster is supported for lateral motion with respect to associated springs, and has shoes on either side thereof between said bolster and the associated guide columns, said shoes comprising cylindrical outer surfaces terminating in radial flanges embracing the guide columns, with the provision of clearance for a limited amount of angling with respect to said columns, whereby said shoes angle with said bolster while permitting the bolster to move laterally therebetween, the flanges on said shoes and the adjacent side surfaces of said columns being radial from the vertical axes of the side frames.

A still further object of my invention is the provision of a railway truck in which the bolster end portions are supported on spring caps by rolling means, allowing for a limited amount of lateral motion, said spring caps also supporting, and being interlocked with, the lower portions of shoes lying at either side of said bolster, said shoes having their upper portions notched, and said bolster having outstanding lugs lying in said notches, with the provision of clearance for allowing the desired lateral motion of said bolster, said bolster having guide lugs near its ends, preferably outside the side frames with which it is assembled, and spaced from the outer surfaces

of said shoes by an amount substantially equal to the desired lateral movement of the bolster with respect to side frames and shoes and adapted to abut the said outer surfaces of the shoes at the limit of such lateral movement. 5

Other objects and advantages of the invention, relating to the particular arrangement and construction of the various parts, will become apparent as the description proceeds.

Referring to the drawings illustrating my invention; 10

Figure 1 is a fragmentary side elevational view of a truck embodying my invention, portions of said bolster and associated parts being shown in transverse section on the line 1—1 of Figure 3, 15 looking in the direction of the arrows;

Figure 2 is a transverse sectional view on the line 2—2 of Figure 1, looking in the direction of the arrows, a portion of the bolster being shown in side elevation; 20

Figure 3 is a fragmentary horizontal sectional view, to a larger scale, on the line 3—3 of Figure 1, looking in the direction of the arrows;

Figure 4 is a fragmentary sectional view on the line 4—4 of Figure 2, looking in the direction 25 of the arrows;

Figure 5 is a fragmentary plan of the lateral motion spring cap;

Figure 6 is a side elevational view of one of the bolster shoes; 30

Figure 7 is a sectional view on the line 7—7 of Figure 6, looking in the direction of the arrows; and

Figure 8 is a bottom plan of the shoe shown in Figure 6. 35

Referring to the drawings in detail, like parts being designated by like reference characters, there is shown a portion of a truck 1, comprising a pair of side frames 2, only one of which is illustrated. Each side frame comprises a compression member 3, a tension member 4, and bolster guide columns 5 spacing intermediate portions of said compression and tension members, and spaced to leave a bolster or window opening 6 therebetween. The outer ends of the compression member are continued beyond the guide columns to join the outer ends of the tension member and connect with journal boxes (not shown) or with journal box holding means (not shown) integral with the ends of the frame. 40

The tension member 4 has an intermediate normally horizontal portion 7 generally box-shaped in section, the upper web portion 8 of which is extended laterally beyond the depending flanges or normally vertical web portions 9 to 55

provide a spring-seating portion of adequate area. The spring-seating portions beyond the flanges 9 are desirably reinforced by triangular gussets 10. The lower web portion 11 beneath the bolster opening 6 may terminate beneath the guide columns, or at approximately such positions, leaving the outer, or inclined, portions of the tension member substantially inverted U-shape in section, as will be understood.

10 The upper web 8 of the tension member is, in the present embodiment, formed with upper longitudinal convolutions or corrugations 12, each of which preferably starts between the guide columns, at a point designated by the reference character 13, and extends diagonally upward and outward, through the corresponding column, to finally merge with the normal plane of the web 8, thereby strengthening the angle between the horizontal and inclined portions of the tension member, as well as providing supplemental or intermediate support for those portions of the tension member between the guide columns. This construction at the same time provides for interlocking between the frame and an associated spring plank, if used.

15 Each guide column 5 desirably comprises a web portion 14 which extends substantially vertically from the compression member to the tension member, the upper portion desirably being inwardly offset toward the other guide column to provide bolster-guiding portions 15. The sides of the guiding portions 15 are defined by flanges 16, extending from the side edges of the web 14, and with their free edges preferably reinforced 20 by heading 17. Said flanges are desirably spaced a greater distance than the width of the convolutions 12 in the tension member, so that they straddle said convolutions and connect with the main web portion 8 of the tension member on 25 either side of said convolutions.

20 In a truck, in which the bolster is connected to the side frames in a manner, for example, as shown in the Kadel Patent No. 1,630,567, of May 31, 1927, the guide columns have guiding portions 25 engaged between lugs on the associated bolster, the planes of engagement being parallel to the longitudinal vertical plane of the side frame. When, through the omission or flexibility of the spring plank, or clearance between said plank 30 and frame, one frame tends to lead the other, the center line of the bolster describes other than a right angle, with the longitudinal vertical plane of the side frame, forming contacts between the corresponding corners of the guide columns and 35 bolster which are theoretically vertical lines. As the bolster moves vertically with reference to the columns under external impulses, causing movement of the supporting springs, it will speedily wear the contacting corners of the columns until 40 sufficient bearing area has been developed, so that any further wear will be at a progressively slower rate. In this process of developing additional wearing surface, the preferred fit clearances between bolster and columns are lost, and 45 the actual clearances become too great for correct alignment of the parts.

45 In order to change such an undesirable condition, I desire to form the flanges 16 on the bolster guiding portions of the columns 5 with guiding surfaces 18 on planes radial, or substantially radial, from the vertical axis 19 of the frame, or line of intersection between the central longitudinal plane of the frame and the central transverse plane thereof. In order to allow for lateral 50 movement of the bolster with respect to the

frame, I form the bolster narrower than the distance between the guiding portions 15, and interpose bolster shoes 20 between the sides of the bolster and said guiding portions.

To provide for the support of the bolster above 5 the horizontal portion 7 of the tension member 4, I desirably employ a spring plate 21 so formed that it nests over the corrugations 12 for interlocking it in place on the tension member 4, said plate desirably having spring-positioning collars 10 22 upstanding therefrom for properly locating the supporting springs 23.

The springs 23 may be provided with an upper spring plate 24, desirably interchangeable with the lower spring plate 21, and resting thereon, is 15 a lateral motion spring cap 25. Said cap desirably has an upper surface of generally conventional character for receiving lateral motion rollers or other anti-friction means 26.

The bolster 21 is of the lateral motion type 20 provided with lower surfaces 28 on its end portions cooperating with the rollers or anti-friction means 26 in a conventional manner. Said bolster, in the present embodiment, is provided with outer guide lugs 29 only, said lugs being spaced 25 from the outer surfaces of the shoes 20 a distance sufficient to allow for the desired amount of lateral movement of said bolster. The outer surfaces 31 of the shoes, or flanges 30 thereof, are desirably parallel to the longitudinal central plane 30 of the frame, and the cooperating or inner surfaces 32 of the lugs 29 are desirably generally parallel thereto, so that, at the limit of lateral movement, there are substantial abutting areas 35 between the parts.

The outer side surfaces 33 of the bolster are desirably parallel, as are the cooperating or inner surfaces 34 of the shoes 20, said surfaces being closely spaced, or having sliding clearance only, so that, while free lateral movement of the bolster 40 between said shoes is permitted within the limits provided, said bolster and associated shoes are otherwise interlocked, so that they tend to angle together with respect to the associated frame.

The flanges 30 of the shoes have inner surfaces 45 35 radial with respect to the axis 19 of the frame, like the adjacent surfaces 18 of the guide columns, with the included angle between the radial shoe surfaces greater than the included angle of the radial column sides, by an amount equal to 50 the angle by which the shoes and associated bolster are permitted to swing from one extreme to the other, upon departure from the normal right angle relationship with respect to the frame. Because of this radial relationship, movement of 55 the bolster to an extreme allowable angular and lateral position will result in contact, with the shoes 20 and between said shoes and guide columns, on generally flat surfaces substantial in extent, rather than the line contact previously referred to. In the present embodiment, however, I have continued this improvement further, as will now be explained.

Instead of making the webs 14 of the guide columns parallel to one another, I have formed 65 the inner surfaces 36 concave to the contour of a vertically disposed cylinder whose axis coincides with the axis 19 of the frame. Each shoe 20 has its outer surface 37 cylindrical about the axis 19 of the frame, the ends of said surfaces merging 70 with the radial surfaces 35 on the outstanding flanges of said shoes along filleted portions at the corners therebetween.

In order to provide for supporting the adapter castings 28, the roller bearing spring cap 25 has 75

outstanding ledges or flanges 38, the outer edge surfaces 39 of which are preferably coaxial with the surfaces 36 on the guide columns, said ledges terminating at notches 40 adapted to receive 5 depending legs or lugs 41 on the lower ends of said shoes 20, which straddle the flanges 38.

In order to prevent the shoes 20 from riding up above the top of the bolster 21, when in service, I provide lugs 42 outstanding from the sides of the 10 bolster and normally lying in notches 43 in the tops of the shoes 20 between upstanding lugs 44 thereon. Sufficient clearance is provided between the lugs 42 on the bolster and the lugs 44 on the shoes in order to allow for the desired 15 lateral motion.

The spring cap 25, in addition to the flanges 38, has outstanding flanges 45, normally embracing the depending legs 41 on the shoes 20, and depending flanges 46 partially defining the periphery of said cap, for properly locating the associated springs 23.

From the foregoing disclosure, it will be seen that I have devised a railway truck in which the bolster is adapted to move laterally with respect 25 to the side frames, while, at the same time, serving to limit movement of said frames away from one another, when assembled, by virtue of the provision of outside guide lugs. Said lugs do not engage the side frames directly at the extreme limits of travel, but shoes or wear pieces 30 interposed between the sides of the bolster and the guide columns, which shoes are supported by spring caps, and so constructed that they are adapted to angle with respect to the associated 35 guide columns, while allowing free lateral movement of the bolster within the limits provided. These shoes are not only supported on the spring cap, but have depending lugs straddling the supporting portions of said cap and lying between 40 end portions and guiding surfaces of the guide columns for holding said cap in place, while allowing it to angle to a limited extent with the shoes, in accordance with the angling movement of the bolster. The bolster is preferably constructed so that portions thereof overlie and 45 interlock with said shoes for maintaining the latter in place.

Although a preferred embodiment of my invention has been disclosed, it will be understood 50 that modifications may be made within the spirit and scope of the appended claims.

I claim:

1. In combination with a side frame having a bolster opening defined by guide columns, a lateral motion bolster received in said opening, a spring cap disposed in said opening below said bolster, anti-friction means supported on said cap and in turn supporting said bolster, and shoes disposed between the sides of said bolster and said 55 guide columns, interlocked with said columns, and supported on said cap, said bolster having lugs extending from upper portions thereof and overlying portions of said shoes to keep the latter in place, clearance being provided for allowing the 60 desired limited motion of said bolster with respect to said frame.

2. In combination with a side frame having a bolster opening, a lateral motion bolster received therein, a spring cap disposed in said opening 65 below said bolster, rollers supported on said cap and in turn supporting said bolster, and shoes disposed between the sides of said bolster and said guide columns, interlocked with said columns, and formed with depending lugs straddling 70 portions of said cap, said bolster having lugs

disposed outwardly of said shoes for limiting lateral movement thereof.

3. In combination with a side frame having a bolster opening defined by guide columns, a lateral motion bolster in said opening, a spring cap disposed in said opening beneath said bolster, rollers supported on said cap and in turn supporting said bolster, and shoes disposed between the sides of said bolster and said guide columns, and interlocked with the latter, said shoes having legs depending below the supported portion thereof, straddling supporting portions of the cap, and lying on either side of the guide columns, and said cap having flanges embracing 10 said legs.

4. In combination with a side frame having a bolster opening defined by guide columns, a lateral motion bolster received in said opening, a spring cap disposed in said opening beneath said bolster, and shoes disposed between the sides 20 of said bolster and said guide columns, said shoes having radial flanges embracing said columns, the adjacent surfaces of said columns being radial and angularly spaced from said flange surfaces, when in normal position, to allow for angular movement therebetween, those portions of said shoes between said flanges being cylindrically coaxial with respect to one another, and the adjacent surfaces of the guide columns being coaxial therewith to cooperate for allowing the desired angular movement of the bolster, said spring cap having lugs underlying said shoes for the support thereof.

5. In combination with a side frame having a bolster opening defined by guide columns, a lateral motion bolster received in said opening, a spring-supported cap disposed in said opening beneath said bolster, said cap having outstanding shelves at the sides thereof and notches at the ends of said shelves, and shoes disposed between 35 the sides of said bolster and said guide columns and resting on said shelves, said shoes having depending lugs received in said notched portions and said bolster having means to keep said shoes down in place on said shelves.

6. In combination with a side frame having a bolster opening defined by guide columns, a lateral motion bolster received in said opening, a spring-supported cap disposed in said opening beneath said bolster, anti-friction means supported on said cap and in turn supporting said bolster, and shoes disposed between the sides of said bolster and said guide columns, said shoes resting on portions of said cap and having notches in the upper portions thereof, said bolster 50 having ears fitting in said notches for preventing undesired upward movement of said shoes, sufficient clearance being provided for lateral movement of said bolster with respect to said 55 shoes.

7. In combination with a side frame having a bolster opening defined by guide columns, a lateral motion bolster received in said opening, a spring cap disposed in said opening beneath said bolster, springs resting on said frame and supporting said cap, anti-friction means supported on said cap and in turn supporting said bolster, and shoes disposed between the sides of said bolster and said guide columns, said shoes having outstanding flanges straddling said columns, the surfaces 60 on said flanges adjacent said columns being radial from the vertical axis of said frame, and the adjacent column surfaces being radial from the same axis, with the included angle between said shoe-flange-surfaces greater than that between 65 75

the column surfaces for allowing angling movement of said shoes with respect to said frame, and corresponding angling movement of the bolster disposed between said shoes.

5. 8. In a railway truck, a side frame comprising a compression member, a tension member, bolster guide columns spacing intermediate portions of said members and spaced to leave a bolster opening therebetween, said guide columns comprising transverse webs and side flanges, a bolster with an end portion received in said opening, and a supporting member underlying said end portion, the bottom surface of said bolster end portion and the top surface of said supporting member having roller seats, rollers engaging said seats for supporting said bolster from said member, and shoes disposed between the sides of said bolster and said columns, said shoes resting on said supporting member and having downwardly extending projections straddling shelf portions thereof, said bolster having lugs received in notches in the upper portions of said shoes, said shoes having outstanding flanges embracing the adjacent portions of said guide columns, and 25 said bolster having lugs spaced from the adjacent flanges for allowing the desired lateral motion of said bolster with respect to said supporting member.

9. In a railway truck, a side frame comprising a compression member, a tension member, bolster guide columns spacing intermediate portions of said members and spaced to leave a bolster opening therebetween, said guide columns comprising transverse webs and side flanges, said webs having adjacent surfaces cylindrically concave about the vertical axis of said frame, and said flanges having outer surfaces radial from said axis, a bolster with an end portion received in said opening, and a spring supported member underlying said end portion, the bottom surface of said bolster end portion and the top surface of said supporting member having roller seats, rollers engaging said seats for supporting said bolster from said member, and shoes disposed between the sides of said bolster and said columns, said shoes comprising web portions with flanges outstanding therefrom, the outer surfaces of said web portions being coaxial with the adjacent surfaces of the columns, and the inner surfaces of the flanges being radial from the axis of the frame, with the included angle between said surfaces greater than the included angle between the radial surfaces on the columns for allowing a desired amount of angling therebetween, said shoes resting on said spring supported member and having projections straddling shelf portions thereof, said bolster having lugs received in notches in the upper portions of said shoes, and lugs spaced from the adjacent flanges on said 50 shoes for allowing the desired lateral motion of said bolster with respect to said supporting member.

10. In combination with a side frame having a bolster opening defined by guide columns, a lateral motion bolster received therein, a spring supported cap disposed in said opening beneath said bolster, rollers supported on said cap and in turn supporting said bolster, said bolster having lugs at the outside only spaced from the columns, with adjacent surfaces on said lugs and columns the surfaces of said bolster lugs being parallel to the longitudinal axis of the side frame and the surfaces of said columns lying on radii from the vertical axis of said frame, and shoes 70 interposed between the sides of said bolster and

said columns having bearing walls coaxial with adjacent bearing walls on said columns for allowing angling movement of said bolster with respect to the side frame, said shoes having inner surfaces cooperating with said column surfaces and outer surfaces cooperating with said bolster lug surfaces. 5

11. In combination with a side frame having a bolster opening defined by guide columns, a bolster received in said opening and spaced from the guide columns, means for supporting said bolster in said opening and allowing for lateral motion thereof, and shoes disposed between the sides of said bolster and said guide columns, said bolster being laterally movable with respect to said shoes 15 but interlocked therewith for angling movement, said shoes and columns having coaxial bearing surfaces to allow for such angling movement.

12. A shoe adapted to lie between a bolster guide column and the adjacent side of a bolster, comprising a web portion with flanges at the sides thereof, said web portion having a flat side and a convex cylindrically curved side, said curved side bulging between said flanges, about an axis substantially parallel to said flanges, and merging into the inner surfaces thereof, said inner surfaces being inclined with respect to one another in planes radial from said axis.

13. A shoe adapted to lie between a bolster guide column and the adjacent side of a bolster, comprising a web portion with flanges at the sides thereof, said web portion having a flat side adapted to engage a corresponding surface on the associated bolster and a convex side cylindrically curved about a substantially vertical axis, said curved side bulging between said flanges and merging with the inner surfaces thereof, said inner surfaces being inclined with respect to one another and each surface co-planar with the corresponding surface on the diagonally opposite 40 flange of a complementary shoe at the other side of said bolster.

14. A spring cap formed with depending portions along the outer and inner periphery thereof adapted to center associated springs and provided 45 with shelves at its sides for supporting bolster shoes, said cap being notched adjacent the ends of said shelves to accommodate depending portions of said shoes for interlocking relation therebetween, and said shelves having arcuate surfaces thereon for permitting horizontal angular movement between said caps and an associated side frame.

15. In combination with a side frame comprising a bolster opening defined by guide columns, a bolster received in said opening, means for supporting said bolster in said opening and allowing for lateral motion thereof, and shoes disposed one at each side of said bolster and cooperating with the respective guide column, said bolster being laterally movable with respect to said shoes but dependent on the relative movement of said shoes with respect to said columns for angling movement of said bolster with respect to said frame, said shoes for that purpose 65 having flanges straddling said columns with the inner surfaces of said flanges and the cooperating surfaces on the columns radial from the vertical axis of the frame, sufficient angular clearance being provided between said cooperating surfaces to allow for the desired angling movement between said shoes and the associated bolster with respect to said frame. 70

16. In a railway truck, in combination with a side frame having a bolster opening defined by 75

guide columns, a bolster received in said opening, means for supporting said bolster, shoes interposed between said guide columns and bolster, said shoes having spaced flanges overlying said 5 guide columns and a notch in the top portion thereof intermediate said flanges, substantially coaxial engaging surfaces on said shoes and guide columns, and said bolster having lugs extending outwardly beyond the sides thereof adapted 10 to occupy said notches for holding said shoes in place.

17. A lateral motion bolster having integral stop faces adjacent its ends, column shoes cooperating with said bolster adjacent each end 15 thereof, said shoes having an outer cylindrically convex surface adapted to engage a correspondingly formed surface on an associated side frame, and a lug projecting from the sides of said bolster adapted to overlie each shoe for preventing the 20 displacement thereof.

18. In combination with a side frame having a bolster opening defined by guide columns, a lateral motion bolster received in said opening, a spring-supported cap disposed in said opening 25 beneath said bolster, movable means interposed between and engaging said bolster and cap, said cap having outstanding shelves at the sides thereof and notches at the ends of said shelves, shoes disposed between the sides of the bolster and 30 said guide columns and resting on said shelves, said shoes having depending lugs occupying said cap notches, flanges on said cap embracing said shoe lugs, and said bolster having outstanding lugs adjacent the upper portion thereof and 35 overlying said shoes to arrest the upward movement thereof.

19. In combination with a side frame having a bolster opening defined by spaced guide columns, a bolster positioned in said opening, a spring cap disposed in said opening beneath said 40

bolster, said bolster having lugs on the ends thereof spaced from said columns, shoes interposed between the sides of the bolster and said columns, flanges on said shoes interposed between said columns and bolster lugs, surfaces 5 on said bolster lugs disposed substantially parallel to the longitudinal axis of the side frame and adapted to cooperate with outer correspondingly formed surfaces on said shoe flanges for limiting transverse movement of said bolster with 10 respect to the side frame, said shoe flanges and guide columns having opposed spaced surfaces substantially radial from the vertical axis of said frame, and substantially coaxial surfaces on said 15 shoes and guide columns to allow for an angling horizontal movement of said bolster with respect to said side frame.

20. In combination with a side frame having a bolster opening defined by guide columns, said 20 guide columns comprising transverse webs having surfaces cylindrically concave about the vertical axis of said frame and side flanges having surfaces radial from said axis, a bolster positioned in said opening, a spring cap disposed in said opening beneath said bolster, resilient means interposed between said frame and cap, and shoes disposed between the sides of said bolster and said guide columns, said shoes having outstanding flanges in straddling relation with said columns and provided with surfaces radial from the 30 vertical axis of said frame, a web portion extending between said shoe flanges having a cylindrically convex surface coaxial with said concave column surface, shelves extending outwardly of said spring cap and intersecting the vertical 35 plane of said shoes, and surfaces on said shelves adjacent and coaxial with said concave column surfaces.

DONALD S. BARROWS. 40
